I.C. Howard,

Fire Place.

Patented Oct. 27, 1835.

John L. Howard

Letters Patent (Plated Octo 27 1835)

The Schedule referred to in these Letters Patent and making part of the same containing a description in the words of the said John L. Howard himself of his improvements in the place for cooking and Baking.

To all whom these Presents shall come - Be it known that J. John L. Howard, of Hampton in the County of Windham, State of Connecticut have invented a new & useful Draw for baking & boiling & that the following is a full and exact description thereof. First - A Grating set in the back of the Chimney eighteen inches or more in length across the Chimney Back.

Second, 1 inches or more from the front of the grate to the back of the same. Third, Eight inches or more from the top of the grate to the bottom of the same to admit the draw. Fourth, Two inches space under the grating & on the back of the grating sufficient room to admit the guides of the draw when shut. Fifth, The grating is of cast iron. Sixth, The draw is made of Sheet or cast iron or Copper, eighteen inches or no more in length. Seven inches or more in width. Eight inches or more deep - with a bag hung on the front of the draw - two iron half inch deep on the lower edge of the draw, with iron guides on the ends running in a groove in the cast grating extending back of the draw, six inches or more to hold the draw while cooking with a cover one inch or more hung on the back side of the draw - fitting within the draw to hold the cover to condense & bake on the top as well as the bottom. Seventhly, The draw is furnished with Baking & Bake pans. That boiling and baking can be done at the same time in the draw.

What I claim as my own invention and not previously known in the above described machine - is a draw passing over grates into the chimney back, boiling and baking with the oven.
